UNITED STATES PATENT OFFICE.

JAMES A. CAMERON, OF BROOKLYN, NEW YORK, ASSIGNOR TO CAMERON MACHINE COMPANY, OF BROOKLYN, NEW YORK, A CORPORATION OF NEW YORK.

SLITTING AND WINDING MACHINE.

Application filed June 1, 1923. Serial No. 642,759.

This invention relates to slitting and winding machines for flexible material and is more particularly an improvement upon the construction shown in Patents Nos. 1,355,106 5 and 1,355,107 which disclose a winding drum having grooves in its surface for separating adjacent slitted sections of flexible material so as to prevent interweaving of adjacent coils.

10 It has been found in practice that when the texture of the flexible material varies slack is sometimes produced at some points laterally of the sections and that, in consequence, the flexible material does not conform 15 to the groove formation of the winding drum. Attempts have been made to overcome this difficulty by employing the expedient of increasing the tension on the web as a whole. When acting on certain materials, however, this expedient is very undesirable.

The main object and feature of this invention is to provide means whereby this tendency to slack may be overcome in connection 25 with a grooved winding drum without applying a relatively heavy tension to the web as a whole.

In the accompanying drawings the invention is disclosed in several concrete and preferred forms in which:

30 Fig. 1 is a vertical sectional view of a portion of one type of slitting and winding machine, showing surface winding means and score-cut slitting means, to which the invention has been applied.

35 Fig. 2 is a diagrammatic view showing another type of slitting and winding machine, in which shear-cut slitting means are employed, embodying the invention.

40 Fig. 3 is a fragmentary face view of the slitting means of Fig. 2.

Fig. 4 is a fragmentary front elevation, with parts broken away and in section, of the parts shown in Fig. 1.

45 Fig. 5 is a view similar to Fig. 1 with the slitting means omitted and showing the take-up device on a large scale.

50 Fig. 6 is a fragmentary view in front elevation of the take-up device showing its action on the flexible material.

Fig. 7 is a front elevation of the winding and slitting means showing a number of slack take-up members and the action of the same on the flexible material.

Figs. 8 and 9 are detail views of the slack 55 take-up shaft and spring.

In the type of machine shown in Figs. 1, 4, 5, 6 and 7 the winding means consist of two surface winding drums 1 and 2 and a winding shaft 3 on which the flexible material is wound into coils in side by side relation in a manner well understood. If desired, a top pressure roll, not shown, may be employed. One of these winding drums, preferably front winding drum 1, is grooved in the manner and for the purpose described in the Letters Patent above referred to. 4 is a tension roller over which the flexible material passes before it reaches the winding means, and, in the present case, this tension roller forms also a backing roller for the score cutters 5. The construction of the score cutters forms no part of the present invention being claimed in the application of Cameron and Birch filed August 25, 1920, 75 Ser. No. 405,997, and in the application of Johnstone Ser. No. 636,134 filed May 2, 1923.

Interposed between the slitting means and the grooved winding drum is a slack take-up device 6. This device consists here of 80 a series of members, their number depending upon the number of slits in the paper, each of which may be, and here is, constructed as follows: Mounted upon a stationary part of the machine, such as I-beam 7, is a bracket 8 that carries a shaft 9. Mounted loosely on this shaft is a member 10 in the form of an arm having a curved face 11. A spring 12 surrounds shaft 9 and has one end bearing on arm 10 and the other anchored on 85 adjustable member 13 which latter is in slotted engagement with pin 25 of shaft 9. The pressure of this spring urges curved face 11 against the slitted sections 14. A latch 15 pivoted at 16 on member 10 provides a means whereby when member 10 is moved back, as shown in dotted lines in 90 Fig. 1, said latch may be placed against the bracket to overcome the tension of the spring and hold said member in its retracted 95 position. The spring tension on each member 10 can be individually adjusted.

I have found that, in order to obtain adequate separation of the slitted sections, it is only necessary that the flexible material 105 shall enter a few grooves adjacent each slit, and I have found that, by straddling each curved plate 11 with respect to the slit be-

tween two sections, proper conformation of the flexible material with a sufficient number of grooves is effected. In Figs. 6 and 7 is shown the action obtained.

5 In Figs. 2 and 3 the invention is shown applied to a shear-cut slitting machine. As here disclosed, 1 and 2 indicate the surface winding drums and 3 the winding shaft. Drum 1 is grooved. 4 is the tension roller, 10 here separate from the overlapping shear cutters 17. 6 indicates the slack take-up device.

I claim:

1. The combination with winding means 15 including a winding drum having grooves for separating slitted sections of flexible material, of a slack take-up device bearing against the slitted sections on both sides of the slit to compel said sections to enter the 20 grooves of the drum adjacent the line of slitting.

2. The combination with winding means 25 including a winding drum having grooves for separating slitted sections of flexible material, of a slack take-up device consisting of a pivotally supported bearing member engaging the slitted sections on both sides of

the slit, and spring means for resiliently urging said bearing member against the sections.

3. The combination with winding means including a winding drum having grooves for separating slitted sections of flexible material, of a slack take-up device consisting of a pivotally supported bearing member engaging the slitted sections on both sides of the slit, spring means for resiliently urging said bearing member against the sections, and a latch for overcoming the action of the spring means to hold the bearing member 40 in inoperative position.

4. The combination with winding means including a winding drum having grooves for separating slitted sections of flexible material, of a slack take-up device consisting 45 of a plurality of individually spring pressed members each straddling a slit and bearing against adjacent slitted sections to compel said sections to enter the grooves of the drum adjacent the line of slitting.

Signed at Brooklyn in the county of Kings and State of New York, this 18th day of May, 1923.

JAMES A. CAMERON.
